UNITED STATES PATENT OFFICE.

CHARLES R. STURDEVANT, OF WORCESTER, MASSACHUSETTS, ASSIGNOR TO THE AMERICAN STEEL & WIRE COMPANY, OF PITTSBURG, PENNSYLVANIA, A CORPORATION OF NEW JERSEY.

RAIL-BOND.

976,947.

Specification of Letters Patent. Patented Nov. 29, 1910.

Application filed June 25, 1910. Serial No. 438,863.

To all whom it may concern:

Be it known that I, CHARLES R. STURDEVANT, of Worcester, in the county of Worcester and State of Massachusetts, have invented a new and useful Rail-Bond, of which the following is a full, clear, and exact description, reference being had to the accompanying drawings, forming part of this specification.

10 My invention relates to rail bonds used to connect the ends of the rails for electric rail-ways, and the object of this invention is to provide a rail bond of improved construction having novel means for forming and 15 stiffening the wires or conductors connecting the terminals.

A further object of the invention is to provide a rail bond having novel means by which the conductivity of the bond is increased.

Referring to the drawings, Figure 1 is a horizontal cross section showing the joint between the ends of two track rails with a rail bond, constructed in accordance with my 25 invention, as applied for use in connecting the ends of the rails. Fig. 2 is a detail sectional plan showing one end of a rail bond having a tubular terminal, constructed and arranged in accordance with my invention. Fig. 3 is a similar view showing a like rail bond, the bend on the connecting end of the flexible member differing from that shown in Fig. 2. Figs. 4 and 5 are plans showing rail bonds having conductor ends constructed in accordance with my invention. Fig. 30 6 is a face view of the terminal shown in Fig. 5. Fig. 7 is a transverse section, and Fig. 8 is a side elevation partly broken away, of a rail joint showing a modified form of 35 rail bond secured in place in connecting the ends of the rails, the flexible connector in this type of bond being formed of parallel strips of copper of rectangular cross section instead of round wires, as in the preceding 40 figures.

In the drawings, referring to Fig. 1, the numerals 2 and 3 designate the web of two rails, the ends of which are connected by means of splice plates 4 and bolts 5. Se- 50 cured in suitable openings in the web of the rails is a rail bond having solid terminals 6 which are permanently secured on opposite ends of a flexible connector 7 which is preferably made of a piece of copper cable.

55 Instead of the terminals 6 being solid as

shown in Figs. 1, 4, 5 and 6, they may be tubular, as shown in Figs. 2 and 3, the flexible portion of these bonds being made of a piece of cable of suitable length, in the same manner as the bond illustrated in Fig. 1. In Figs. 7 and 8, the ends of the rails 8, 8, are shown connected by splice plates 9 and 10, and bolts 11. Instead of the rail bond being outside of the splice bars as in Fig. 1, the bond is inserted and secured in place in the openings provided in the ends of the rails 8, before the splice plate 9 is put into place. The terminals 12 on this bond are secured together by a flexible connector 13, which in this case is made up of thin flat 60 strips of copper instead of a piece of cable or rope 7, in which the strands are made up of a plurality of wires which are cylindrical in cross section.

In constructing the rail bonds in accordance with my invention, the terminals are first attached to the conductors by forging or casting, or otherwise. The ends of the rail bonds are then coated or covered with a fluxing material and the terminals and adjoining end portions of the flexible conductors are then dipped into a molten bath of soldering tin alloy which firmly secures and unites the conductor or connector wires into a solid mass for any desired length back of 70 the terminals. The part of the conductor adjoining the terminal is bent into the desired shape or degree of curvature, preferably before the dipping operations. The cross sectional area of the conductors at 75 their ends is increased by the dipping operation, in this way increasing the conductivity of the bond, and the coating of solder acquired in this way improves and also makes a more rigid connection between the flexible 80 member and the terminals. An improved union between the terminal and flexible portion is thus obtained and the conductivity of 85 the bond is increased.

The advantages of my invention will be 90 apparent to those skilled in the art. The bonds may be quickly and cheaply treated, the end portions of the flexible connector are permanently and rigidly formed into any desired bend or shape, an improved union 95 between the terminal and conductor portions is obtained, while by the addition of more metal to the terminal ends of the conductor, the conductivity of the bond is increased.

Modifications in the construction and ar- 110

angement of the parts may be made without departing from my invention. The shape and type of the terminals may be changed and the flexible member may be 5 made of materials other than a strand of copper wires or copper strips, as described.

I claim:—

1. A rail bond comprising a flexible member having terminals secured to the end thereof, the terminals and adjoining ends of the conductor being coated with solder, the solder extending any desired distance on the connector beyond the terminals toward the center of the length of the bond to stiffen and maintain its ends in the shape into which the bond is bent; substantially as described.
2. A rail bond comprising a flexible member having terminals secured to the ends thereof and a layer of solder on the ends of the bond adapted to stiffen and increase the conductivity of the ends of said flexible member; substantially as described.
3. A rail bond comprising a strand of wire having a plurality of wires forming a flexible connector, solid terminals on the ends thereof and a coating of solder on the

ends of the strand adapted to stiffen and unite the wires adjacent to the terminals into a solid connector; substantially as described. 30

4. A rail bond comprising solid terminals connecting the ends of a flexible member, and a coating of solder extending inwardly from the ends of the flexible member toward the center of its length for stiffening and maintaining the coated portions thereof in the bent shape into which such portions are formed; substantially as described. 35

5. A rail bond comprising solid terminals connecting the ends of a plurality of wires forming a flexible conductor therefor and a coating of solder on the ends of the flexible connector adjacent to the terminals to stiffen and maintain the solder coated end portions 40 of the connector in the desired curved shape to which such end portions are bent; substantially as described.

In testimony whereof, I have hereunto set my hand.

CHARLES R. STURDEVANT.
